UNITED STATES PATENT OFFICE.

EDWARD H. FUNKE, JR., OF BLUE HILL, NEBRASKA.

DISPLAY-RACK.

1,256,465.

Specification of Letters Patent. Patented Feb. 12, 1918.

Application filed April 14, 1917. Serial No. 162,019.

To all whom it may concern:

Be it known that I, EDWARD H. FUNKE, Jr., a citizen of the United States, residing at Blue Hill, in the county of Webster and 5 State of Nebraska, have invented certain new and useful Improvements in Display-Racks; and I do hereby declare the following to be a full, clear, and exact description of the invention, such as will enable others 10 skilled in the art to which it appertains to make and use the same.

This invention relates to display racks and has for its principal object to provide one on which is swingingly mounted a plurality of display frames, suitable adjusting means being provided whereby when the display frames are swung consecutively from their normal position to a display position, they will all when released automatically 20 swing back to their normal position.

A further object of the invention is to provide the bottom of the display rack with a plurality of supporting hooks and to provide the top of the rack with a longitudinally adjustable bar on which is arranged 25 a plurality of hooks, which together with the hooks at the bottom of the rack are designed to support a plurality of display frames, whereby when the bar is adjusted 30 in either direction to move the upper hook out of vertical alinement with the lower hooks, all of the display frames will automatically swing to their normal position when released in displayed position.

35 A still further object of the invention is to provide a display rack with suitable stops which serve to limit the swinging movement of the display frames.

A still further object of the invention is 40 to provide each of the display frames with removable display cards.

With these and other objects in view as will appear as the description proceeds, the invention comprises the various novel features of construction, combination and arrangement of parts as will be more fully described hereinafter and set forth with particularity in the appended claims.

Referring to the drawings,

50 Figure 1 is a front elevation of my improved construction of display rack.

Fig. 2 is an end elevation thereof.

Fig. 3 is a plan view of the display rack.

55 Fig. 4 is a fragmentary front elevation of the display rack showing how the dis-

play frames may be adjusted to operate from either side of the rack.

Fig. 5 is a transverse sectional view through one of the display frames, and

Fig. 6 is a fragmentary perspective view 60 showing the means for adjusting the longitudinally movable bar.

Similar characters of reference are used to denote like parts throughout the accompanying drawings and the following de- 65 scription.

Referring more particularly to the drawings, it will be seen that my novel construction of display rack embodies in this instance a substantially rectangular frame 70 comprising lower and upper bars 1 and 2, and end bars 3, respectively. The frame is supported and braced by legs 4, and arranged within the frame in the lower opposite corners are triangular braces 5 which 75 serve to add rigidity to the structure.

The upper bar 2 of the frame has a longitudinally movable and adjustable bar 6 attached to its under surface, this bar being provided throughout its length with a plurality of supporting hooks 7. The upper bar 2 carries threaded studs or bolts 8 which project downwardly through slots 9 in the bar 6 and have wing nuts 10 connected to their outer ends whereby the bar 6 may 80 be clamped in any adjusted position. A bearing washer 11 is interposed between each of the wing nuts 10 and the bar 6.

A lower bar 1 is also provided throughout its length with a plurality of supporting hooks 11', these hooks together with the hooks 7 serving to support a plurality of display frames 12, each of these frames 12 being provided at its opposite ends with eye bolts 13 which are positioned over the 95 hooks 7 and 11 respectively.

When it is desired to display the articles mounted upon the display frames from the position shown in Fig. 1, the bar 6 is adjusted to the left so that the hooks 7 will be 100 out of vertical alinement with the hooks 11, thus assuming the dotted line position shown in Fig. 4 of the drawings. After the bar 6 has been adjusted, the display frames 12 are 105 swung one by one from the left to the right and after they have all been swung to the right they will immediately upon being released automatically swing back to the left to their normal position by virtue of the adjustment of the bar 6.

In some instances it might be undesirable to have the display frames swing from the left to the right, by reason of the position of the display rack with respect to some adjacent articles or store fixtures where the rack may happen to be displayed, and when such is the case the bar 6 may be adjusted in the opposite direction so that the display frames will be normally positioned on the right of the rack and will automatically swing from the left to the right after having been displayed to the perspective buyer. When the display frames have been adjusted to assume this latter normal position, they will normally hang in the position shown in Fig. 4 by full lines.

In order to hold and maintain the display frames in their normal position I provide a substantially triangular stop 14 which is provided with an aperture to receive a vertically disposed pin 15 that is positioned within the upper edge of one of the supporting legs 4. The other supporting leg 4 is also provided in its upper edge with a vertically disposed pin 16 and serves as a stop for the frames when they are swung from their normal to a displayed position. When all of the frames have been swung into engagement with the stop pin 16, they will when released all swing automatically back to their normal position. When the display rack is adjusted so that the display frames will swing from the left to the right instead of the right to the left, the triangular stop 14 is removed from the pin 15 and positioned upon the pin 16 so as to form a proper stop for the frames in this reversed position, the pin 15 then serving as a stop for the frames in displayed position.

Each of the display frames 12, in this instance is provided in its inner circumferential edges with a pair of grooves 17 into which are sprung sheets of cardboard 18 and on which are adapted to be arranged the goods to be displayed.

Arranged upon the upper bar 2 is a suitable frame 19 which is adapted to contain an advertising card 20 on which may be printed and displayed the name or names of the articles mounted on the display frames.

From the foregoing description, taken in

connection with the accompanying drawing, the advantages of construction and method of operation will be readily apparent to those skilled in the art to which the invention relates, and while I have described the principle of the operation of the invention, together with the device which I now consider to be the best embodiment thereof, I desire to have it understood that such changes in construction may be made when desired as are within the scope of the appended claims.

What I claim is:

1. A display rack comprising a frame, a plurality of display frames swingingly mounted upon said frame, and means for adjusting the upper ends of said frames laterally whereby when the frames have been moved to displayed position, they will, as soon as released automatically swing back to their normal position.

2. A display rack comprising a frame, supporting means carried by the bottom of said frame, a bar carried by the top of said frame, supporting means arranged upon said bar, a plurality of display frames swingingly supported on said supporting means of the bar and the bottom of the frame, and means for adjusting said bar longitudinally in either direction.

3. A display rack comprising a main frame, transverse supporting legs for the opposite ends of said main frame, a stop pin projecting upwardly from each supporting leg, a substantially triangular stop member having an aperture and adapted to be selectively positioned over each of said stop pins, and display frames swingingly mounted on said main frame and adapted to engage said stop member at one end of the main frame and the stop pin at the other end of the main frame to limit their swinging movements in opposite directions.

In testimony whereof I have signed my name to this specification in the presence of two subscribing witnesses.

EDWARD H. FUNKE, JR.
